United States Patent Office

Des. 233,856
Patented Dec. 3, 1974

233,856

FILM STRIP PROJECTOR

Hiroshi Kira, Oxnard, Calif., assignor to Norman Holtzman, Los Angeles, Calif.

Filed June 18, 1973, Ser. No. 371,283

Term of patent 14 years

Int. Cl. D16—02

U.S. Cl. D61—1 J

FIG. 1

FIG. 2

FIG. 1 is a left front perspective view of a film strip projector showing my new design;

FIG. 2 is a right rear perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view thereof; and

FIG. 8 is a rear elevational view thereof.

I claim:

The ornamental design for a film strip projector, substantially as shown.
